Primary Examiner — Charles Hanson(74) *Attorney, Agent, or Firm* — Holtz, Holtz & Volek PC(57) **CLAIM**

The ornamental design for a bone insert, as shown and described.

DESCRIPTION

FIG. 1 is a front and top perspective view of a bone insert for use on the left side of a body, showing my new design; FIG. 2 is right side view thereof; FIG. 3 is a left side view thereof; FIG. 4 is a top view thereof; FIG. 5 is a bottom view thereof; FIG. 6 is a rear view thereof; FIG. 7 is a front view thereof; FIG. 8 is a front and top perspective view of a bone insert for use on the right side of a body; FIG. 9 is a left side view thereof; FIG. 10 is a right side view thereof; FIG. 11 is a top view thereof; FIG. 12 is a bottom view thereof; FIG. 13 is a rear view thereof; and, FIG. 14 is a front view thereof.

The broken lines immediately adjacent to the shaded areas represent the bounds of the claimed design while all other broken lines represent environmental structure and are for illustrative purposes only; the broken lines form no part of the claimed design.
